UNITED STATES PATENT OFFICE.

HENRY C. SCHWARZ, OF NORWALK, OHIO.

PIANO-ACTION.

SPECIFICATION forming part of Letters Patent No. 671,566, dated April 9, 1901.

Application filed December 18, 1900. Serial No. 40,283. (No model.)

To all whom it may concern.

Be it known that I, HENRY C. SCHWARZ, a resident of Norwalk, in the county of Huron and State of Ohio, have invented certain new 5 and useful Improvements in Piano-Actions; and I do hereby declare the following to be a full, clear, and exact description of the invention, such as will enable others skilled in the art to which it appertains to make and 10 use the same.

My invention relates to an improvement in piano-actions, the object of the invention being to provide improved means for preventing lost motion to the action when the soft 15 pedal is operated and make the hammers as sensitive to a touch on the keys with the soft pedal depressed as when in its normal raised position; and with this object in view the invention consists in certain novel features of 20 construction and combinations and arrangements of parts, as will be more fully herein-after described, and pointed out in the claims.

In the accompanying drawings, Figure 1 is a view in side elevation, showing the parts in 25 their normal position. Fig. 2 is a similar view showing the position of the parts when the soft pedal is operated, and Figs. 3, 4, and 5 are enlarged views of details of construction.

1 represents a frame to which is secured 30 the action-rail 2. The hammer-butt 3, carrying hammer 4, is pivotally connected to the upper edge of rail 2, and my improved whippen or whip 5 is pivotally connected at one 35 end to said rail 2 and projects out beyond the same and has pivotally mounted thereon the jack 6, disposed against the hammer-butt 3, as shown.

A hammer-rail 7 for limiting the movement 40 of the hammers is normally supported on the frame 1, and an adjusting-bar 8 is connected at its upper edge, by hinges 9, with arms 10^a on frame 1 slightly below the whippen or whip 5, and a rod 10 is pivotally connected at its upper end to hammer-rail 7 and at its 45 lower end adjustably secured to a bracket 11, having slight universal connection with bar 8 by means of a spool 12, disposed in an opening in the bracket 11 and secured to the bar 8 by a screw, as shown.

50 13 represents a piano-key provided on its inner end with the ordinary capstan 14, on which the lower end of the push-rod 15 rests,

the upper end of which latter is held against the lower face of the whippen or whip 5, and is connected near its lower end to a bar 16 on 55 frame 1 by a link 17 and near its upper end to the adjusting-bar 8 by means of a series of pivotally-connected links 18.

The under face of the whippen or whip 5, against which the upper end of push-rod 15 60 rests, is curved in the arc of a circle eccentric with the lower end of said rod 15, so as to raise the whippen or whip slightly when the rail 7 is raised, as will more fully hereinafter appear, and the rail 7 is connected 65 with the soft pedal (not shown) by means of a rod or rods 19, so that when the soft pedal is depressed the rail 7 will be raised to the position shown in Fig. 2.

The operation of my improvements is as 70 follows: When the soft pedal is depressed, the rod or rods 19 will force rail 7 up from its supports and hold the same and hammers resting thereon in the position shown in Fig. 2. The raising of rail 7 will, through the me- 75 dium of rod or rods 10, swing bar 8 on its hinge 9 and pull the links 18 outward, thus drawing the upper end of push-rod 15 outward to the position shown in Fig. 2, and owing to the curved under face of the whip- 80 pen or whip 5 will raise the same slightly, so as to maintain the upper end of the jack 6 against the hammer-butt 3 and at the same time not affect the position of the key 13 in the slightest. It will thus be seen that there 85 will be no lost motion whatever and that the operation of the hammer will be as sensitive to a touch on the keys when the soft pedal is depressed as when it is in its normal position.

Various slight changes might be resorted 90 to in the general form and arrangement of the several parts described without departing from the spirit and scope of my invention, and hence I would have it understood that I do not wish to limit myself to the precise details set forth, but consider myself at 95 liberty to make such slight changes and alterations as fairly fall within the spirit and scope of my invention.

Having fully described my invention, what 100 I claim as new, and desire to secure by Letters Patent, is—

1. In a piano-action, the combination with a hammer and a support therefor, of a whip-

pen or whip having its lower face curved in the arc of a circle, a jack supported thereon for operating the hammer, a push-rod disposed against the curved under face of the 5 whippen or whip, a key for operating said rod and means connecting the upper end of the push-rod and hammer-support for moving the upper end of the rod on the curved under face of the whippen or whip when the hammer-support is raised.

2. In a piano-action, the combination with a hammer, a movable support therefor, a key and a push-rod supported at its lower end on 15 said key, of a whippen or whip having its under or lower face curved in the arc of a circle eccentric with the lower end of said rod and with which the upper end of the rod engages, a jack on said whippen or whip to engage the hammer, and means connected with 20 the hammer-support for drawing the upper end of the push-rod outward to raise the whippen or whip slightly to compensate for the raising of the hammer, when the hammer-support is raised.

25 3. In a piano-action, the combination with a frame, an action-rail secured thereto, a hammer pivoted to the upper edge of the rail, a whippen or whip pivotally connected at one end to the lower edge of the action- 30 rail and having a curved lower face, and a

jack on said whippen or whip in engagement with the hammer, of a hammer-supporting rail supported on the frame and adapted to be raised by the soft pedal, an adjusting-bar hinged to the frame below the whippen or 35 whip, a rod connecting the hammer-supporting bar and adjusting-bar, a key, a push-rod on said key and disposed against the curved lower face of the whippen or whip, a link connecting the push-rod near its lower end 40 with the frame, and a series of pivoted links connecting the push-rod near its upper end with the adjusting-bar.

4. In a piano-action, the combination with a movable hammer-support, a whippen having a curved under face, a key and a push-rod bearing against the curved face of the whippen and arranged to be actuated by the key, of a 45 hinged bar, a connection between said bar and the push-rod, and a rod connected at one 50 end with the hammer-support and having a hinge connection at its other end with said hinged bar.

In testimony whereof I have signed this specification in the presence of two subscribing witnesses.

HENRY C. SCHWARZ.
